UNITED STATES PATENT OFFICE.

THOMAS H. LEWIS, OF PANA, ILLINOIS, ASSIGNOR OF THREE-TENTHS TO J. J. PIERPONT, OF PANA, ILLINOIS.

CAR-COUPLING.

1,241,131.

Specification of Letters Patent. Patented Sept. 25, 1917.

Application filed March 29, 1917. Serial No. 158,281.

To all whom it may concern:

Be it known that I, THOMAS H. LEWIS, a citizen of the United States, residing at Pana, in the county of Christian, State of Illinois, have invented a new and useful Car-Coupling; and I do hereby declare the following to be a full, clear, and exact description of the invention, such as will enable others skilled in the art to which it applies to make and use the same.

This invention relates to an improved car coupler, and means for operating the same, and an object of the invention is to provide means whereby the coupler may be operated from the side or the top of the car.

Another object of the invention is to provide a pivoted knuckle member to be engaged by a corresponding member of the coupling element of an adjacent car, in combination with a spring tensioned sliding dog to hold the knuckle member in place, that is, when both members of a pair of couplers are in engagement.

In practical fields, the details of construction may necessitate alterations falling within the scope of what is claimed.

The invention comprises further features and combination of parts, as hereinafter set forth, shown in the drawings, and claimed.

30. In the drawings:—

Figure 1 is an end elevation of a car, showing one of the couplers, and the means for operating the sliding dog, whereby the pivoted knuckle may be released.

35. Fig. 2 is a view in side elevation of two adjacent cars, showing the couplers connected, and the means for operating the sliding dog to release the pivoted knuckle.

Fig. 3 is a detail perspective view of the 40 lower end of a vertically disposed pivoted member, and the inner end of a horizontally disposed pivoted member, for actuating the lever, (shown in dotted lines), which operates the sliding dog.

45. Fig. 4 is a plan view of the couplers, showing them separated.

Fig. 5 is a sectional view of said couplers, showing them connected.

Fig. 6 is a view of one coupler, showing 50 parts in section and parts in elevation, in illustrating the lever for actuating the dog.

Fig. 7 is a view similar to Fig. 6, showing the dog as having been actuated.

Referring more especially to the drawings, 1 and 2 designate adjacent cars, and 3

and 4 denote the coupling bars carried by the cars, and having the couplers 6. Each coupler 6 is provided with side arms 9 and 10, and a recess 11 between the two arms, to receive a knuckle 13 of a coöperating 60 coupler. The arm 10 of the coupler is provided with a bifurcation 12, in which a knuckle is provided on a pin 14. When it is desired to couple the cars, the knuckles of both couplers are disposed, as shown in 65 Fig. 4. The cars are then moved toward each other, in which case, the inner edge of the arm 9 of each coupler head will co-operate with the outer curved edge of the curved portion 15 of the opposite knuckle, 70 guiding said portion 15 toward and into the recess 11. As the curved portion 15 enters the recess 11, substantially the extremity of the curved portion 15 will so coöperate with the tail of the opposite knuckle, as to actuate a sliding dog 17 sufficiently so that the nose of the dog will assume a position in the path of the tail of the knuckle, that is, after the tail has cammed over the nose of the dog. In this way the curved portion 15 of 80 both knuckles are thrown into coöperation, as seen in Fig. 5, thereby coupling the cars. The coupling bar 4 is provided with a bar 16, rectangular in cross section, to receive the sliding dog 17, and formed vertically in the bar 4 near the head of the coupler and across the bore, is a slot or opening 18. Pivoted upon a pin 19 of the lower parts of the walls of said slot or opening 18 is the lower end of the lever 20, which passes through an opening 21 in the sliding dog. This opening 21 is of less length than the slot 18, as is shown clearly in Fig. 7. Arranged in the bore 16 between its end 22 and one end of the sliding dog, is a coil spring 23, to hold the nose 24 of the dog beyond the crotch of the recess 11, whereby said nose will assume a position in a path of the end 25 of the tail 26 of the pivoted knuckle, 90 thereby holding the curved part 15 of one knuckle in engagement with a corresponding curved part of the coöperating knuckle, so as to hold the two couplers connected. A bracket 27 is secured upon the end of each car, and pivoted upon the bracket by means of a pivot bolt 29, is a member 30. The lower extremity of the pivoted member 30 is provided with a forked end 41, the V-shaped recess between the forks being designed to receive and engage the pivoted 100 105 110

lever 20, so that when the pivoted member 30 is moved in the direction of the arrow *b*, the forked end 41 will bear against and tilt the lever 20, thereby sliding the dog 17 5 against the action of its spring, so that its nose will move from the path of the extremity of the tail 26 of the pivoted knuckle 13. Therefore, just so soon as the pivoted knuckle is so released, and one or the other of 10 said cars is moved, from its adjacent car, the couplers will uncouple. In other words, one or the other of the knuckles may be released by sliding its dog from the path of its tail, or both dogs may be moved so as to release 15 both knuckles simultaneously, which will permit the uncoupling of the cars. Mounted upon the ends of the car 1 near the lower part thereof, is a bracket 42, similar to the bracket 27, and pivoted upon the bolt 43 20 of the bracket 42, is a pivoted member 44, having the forked end 45, to engage and operate the lever 20, in order to actuate the sliding dog from the side portion of the car.

The invention having been set forth, what 25 is claimed as new and useful, is:—

In a car coupler, a pair of draw bars having adjacent coupler heads, a pair of knuckles pivoted diagonally in said coupler heads and adapted to interlock, said draw bars

having bores or hollows rectangular in cross section extending back from the heads, a spring tensioned bolt rectangular in cross section slidably fitting said bore or hollow to hold its knuckle in engagement with the adjacent knuckle and having a slot midway 35 its ends, one end of said slot having a rounded or curved bearing surface, said draw bar having its upper and lower walls provided with registering slots with which the slot of the bolt substantially registers, 40 and a straight lever having its lower end pivoted in the lower slot of the draw bar and projecting through the slot of the bolt and the upper slot of the draw bar, and extending upwardly beyond the plane of 45 the upper surface of the coupler head, whereby it may be engaged and oscillated by an oscillated lever, thereby causing the pivoted lever to ride against said rounded or curved bearing surface. 50

In testimony whereof I have signed my name to this specification in the presence of two subscribing witnesses.

THOMAS H. LEWIS.
